UNITED STATES PATENT OFFICE

165,568

LIQUID DISPENSER

Frank Bartolucci, Jr., New York, N. Y.

Application January 14, 1950, Serial No. 7,262

Term of patent 14 years

(Cl. D58—26)

To all whom it may concern:

Be it known that I, Frank Bartolucci, Jr., a citizen of the United States, and a resident of the city, county, and State of New York, have invented a new, original, and ornamental Design for a Liquid Dispenser, of which the following is a specification, reference being had to the accompanying drawing, forming a part hereof, in which:

Fig. 1 is a perspective view of a liquid dispenser embodying my new design; and

Fig. 2 is a view in side elevation of the same.

The dominant feature of my design resides in that portion shown in full lines in the drawing.

I claim:

The ornamental design for a liquid dispenser, as shown and described.

FRANK BARTOLUCCI, JR.
